TIE FORM

Louis Zussman, Kirkwood, Mo.

Application October 11, 1947, Serial No. 779,300

1 Claim. (Cl. 2—153)

1

The present invention relates generally to necktie supporting and shaping devices, and more particularly to a necktie form for shaping a knot and supporting a necktie of the four-in-hand type for immediate application to and removal from a shirt collar.

An object of the present invention is to provide a novel tie form which is constructed to receive a four-in-hand tie in a manner to shape the knot and to support the tie in a manner for application to and removal from the collar of a shirt.

Another object is to provide a novel tie form which is designed to shape a Windsor knot and to support the knotted tie for wear.

Another object is to provide a novel tie form which is contoured to have a four-in-hand tie knotted thereon and to support the tie in wearing relation to a shirt collar.

Another object is to provide a novel tie form which is contoured to have a four-in-hand type tie knotted thereon in permanent relation, thereby saving wear and tear on the tie which results from the numerous typings and un typings thereof when worn in the usual manner.

Other objects are to provide a novel tie form which readily adapts a four-in-hand tie to a collar, which provides a full knot of desired depth, which is inexpensive to make and which may be retailed for a low price, which may be supported by elastic bands, or the like, in wearing position against a shirt collar, and which insures a neat knot for the wearer.

The foregoing and other objects and advantages are apparent from the following description taken with the accompanying drawing, in which:

Fig. 1 is a front view of a tie form constructed in accordance with the teachings of the present invention, with a four-in-hand tie knotted thereon by a Windsor knot;

Fig. 2 is a rear view thereof, elastic supporting means being indicated in broken lines;

Fig. 3 is an enlarged front view of the tie form;

Fig. 4 is a rear view thereof;

Fig. 5 is an end view thereof;

Fig. 6 is a section on the line 6—6 of Fig. 3, looking in the direction of the arrows;

Fig. 7 is a cross-sectional view taken on the line 7—7 of Fig. 3, looking in the direction of the arrows; and

Fig. 8 is a cross-sectional view on the line 8—8 of Fig. 3.

Referring to the drawing more particularly by reference numerals, 10 indicates generally a tie form incorporating the teachings of the present

2

invention. The form 10 includes a supporting portion 12 of arcuate form and a depending central knot forming portion 14.

The supporting portion 12 includes oppositely extending wings 15 and 16, each of which has an aperture 17 therethrough near the free end thereof. Each aperture 17 is adapted to receive one of two hook members connected by an elastic band, or to receive one end of an elastic member 18 such as is usually employed with bow ties, or the like, it being understood that one member 18 will include a hook and the other a hook-receiving loop in the well-known manner.

The depending portion 14 is of generally triangular shape (Figs. 3 and 4) and is of arcuate transverse cross section, as is clear from Figs. 6 through 8. The depending portion 14 is joined to the supporting portion 12 by an off-center neck 20, in effect, thus providing a shallow notch 21 and a deep notch 22. The angle between the depending portion 14 and the supporting portion 12 may be varied from that shown in the drawing. As shown, the depending portion 14 will lift the tie knot from the shirt; for closer wear, the depending portion 14 may be formed at an acute angle to the supporting portion 12.

The depending portion 14 is shown of a form particularly adapted to shape a Windsor knot; a Windsor knot 24 being shown in Figs. 1 and 2 securing a tie 26 to the tie form 10. Manifestly, the depending portion 14 may be varied in shape. It is to be noted that the transverse arcuate cross section of the depending portion 14 insures a full-bodied knot.

In applying the tie 26 to the form 10, the Windsor knot is formed in the usual manner of tying such a knot. The notches 21 and 22 anchor the tie material in the initial phases of the knot. The larger notch 22 also provides for receiving surplus material at this side of the knot and insures a smooth even Windsor knot.

It is contemplated that the tie 26 will remain applied to the form 10, which will facilitate its application of and removal from a shirt collar. Furthermore, a smooth even knot is always available for instant use, it being well recognized generally that a Windsor knot is exceedingly difficult to tie, and, hence, often requires considerable time in its execution. In addition, the mastering of a Windsor knot is indeed difficult and perfection is attained by few.

Since the tie 26 remains on the form 10, wear and tear occasioned by tying and untying is obviated. It is well known that manipulating a tie frays the edges and wrinkles the tied portion.

Manifestly, the tie can be removed when it is required to clean the surface of the knot.

The present tie form 10 may be conveniently made of plastic, although other materials may be employed, if desired.

It is apparent that there has been provided a tie form which fulfills the objects and advantages sought therefor.

It is to be understood that the foregoing description and the accompanying drawing have been given by way of illustration and example. It is also to be understood that changes in form of the elements, rearrangement of parts, and substitution of equivalent elements, which will be obvious to those skilled in the art, are contemplated as within the scope of the present invention which is limited only by the claims which follow.

What is claimed is:

An integral tie form comprising oppositely extending wing portions, and a depending central tie receiving body portion, said body portion being joined to said wing portions by a neck portion of less width than the width of the upper

part of the body portion, there being a tie receiving notch at each side of the neck portion, said neck portion being off-center relative to said body portion and one notch thereby being deeper than the other notch, said body portion being of shield configuration and of arcuate cross section both horizontally and vertically providing a rear cavity within which tie material is received.
